UNITED STATES PATENT OFFICE.

LOUIS G. MILLER AND FREDERICK C. DANKMYER, OF WESTMONT BOROUGH,
PENNSYLVANIA.

UNCOUPLING DEVICE.

1,278,976.

Specification of Letters Patent. Patented Sept. 17, 1918.

Application filed April 25, 1918. Serial No. 230,830.

To all whom it may concern:

Be known that we, LOUIS G. MILLER and FREDERICK C. DANKMYER, both citizens of the United States, and both residing in the borough of Westmont, in the county of Cambria and State of Pennsylvania, have invented certain new and useful Improvements in Uncoupling Devices; and we do hereby declare the following to be a full, clear, and exact description of the invention, such as will enable others skilled in the art to which it appertains to make and use the same.

Our invention relates to uncoupling devices also known as coupler release riggings for use on freight cars, whereby the coupler can be released or engaged without the necessity for the brakeman or switchman going between the cars, thereby conducing to safety.

Our apparatus is of simple construction, readily installed or dis-assembled without cutting out or replacing rivets, screwing the nuts of bolts, or taking off or putting on any auxiliary appurtenances.

We will now, in order to make the matter more clear, refer to the accompanying sheet of drawings in which like characters of reference indicate like parts.

Figure 1 is a front elevation of the uncoupling device and a portion of the end of the car;

Fig. 2 is a top plan view of the device drawn on a larger scale, the end wall of the car being shown in section;

Fig. 3 is a front elevation of the uncoupling device and a portion of the end of the car similar to Fig. 1 but drawn on a larger scale;

Fig. 4 is a transverse sectional elevation taken on the line IV—IV of Fig. 2;

Fig. 5 is a detail vertical transverse section through the uncoupling rod journal bearing taken on the line V—V of Fig. 3;

Fig. 6 illustrates one form of enlarged journal formed integral with the uncoupling rod; and

Fig. 7 illustrates another form of enlarged journal.

Referring now to the characters of reference on the drawings:

1 represents a portion of the car in general, 2 the end sill thereof, 3 the end cover plate, 4 are the journal bearings of our uncoupling device, each provided with a cylind-

rical opening 5 therein and a slot 6 in the upper portion thereof. 7 is an uncoupling rod which is provided with a cylindrical enlargement or journal bearing 8, which either may be formed integral therewith or by means of an annular sleeve mounted thereon, of size adapted to fit within the cylindrical opening in the journal bearings. 9 is the operating arm of the uncoupling rod which is bent at an angle to the body of the rod and also has an offset to allow it to clear the end sill. 10 is the crank arm formed by bending the other end of the rod, and provided with a link 11 mounted thereon, which link is secured in place by the bent ends of the crank arm and connected with the locking pin 12 by means of an eye end, as illustrated. Referring to Fig. 6, the enlargement on the uncoupling rod 7 is formed integral therewith, and as illustrated in Fig. 7, this enlargement is made by riveting the annular sleeve 13 thereto by means of the rivet 14, the rod with the sleeve mounted thereon being 15.

The operation, installation and dis-assembling of our device is as follows:—Assuming the device to be in position, as illustrated, the upward movement of the operating arm 9 will lift the locking pin from the coupler and allow it to be opened in due course of operations and when the couplers are together, the operating arm 9 is turned or drops downwardly, thereby allowing the locking pin to drop into place. When the parts are in position, as shown by the full lines on the drawings, the bent ends of the uncoupling rod 7, namely, the operating arm 9 and the crank arm 10, serve to retain it in operative position and prevent it from moving endwise, as any tendency to move endwise is prevented by the contact of said bent ends with the ends of the journal boxes. The uncoupling rod may have other projections adjacent the journal boxes to retain it in normal position. The parts being in position shown by the full lines in Fig. 1, when it is desired to remove the coupler release rigging, the operating arm 9 is turned upwardly until it is substantially horizontal and beyond its usual upper position when operating, until the crank arm 10 is in a line with the slot 6 of the right-hand journal bearing 4 and the entire rod can then be slid to the left, thereby withdrawing the enlargements 8 or the sleeves 13 from 14.

the journal bearings, and then the rod can be lifted upwardly and the smaller portions of the rod 7 or 15 can be withdrawn through the slots 6 of the two journal bearings 4. The position to which the uncoupling rod is moved in dis-assembling, is shown by the dotted lines in Fig. 1. A reverse operation will mount the rod. It will thus be seen that no bolts or rivets or other parts have to be taken out in order to assemble or dis-assemble the apparatus.

Although we have shown and described our improvements in considerable detail, we do not wish to be limited to the exact and specific details shown and described, but may use such substitutions, modifications or equivalents thereof, as are embraced within the scope of our invention, or as pointed out in the claims.

Having thus described our invention, what we claim and desire to secure by Letters Patent is:—

1. In a coupler release rigging, an uncoupling rod provided with a pair of cylindrical enlargements mounted in journal boxes, provided with slots in their upper surfaces smaller than said enlargements and larger than the body of the rod.

2. In a coupler release rigging, an uncou-

pling rod provided with a pair of cylindrical enlargements mounted in journal boxes, provided with slots in their upper surfaces smaller than said enlargements and larger than the body of the rod, said rod having an operating arm and a crank arm 35 angularly arranged to said rod.

3. In a coupler release rigging, an uncoupling rod provided with a plurality of enlarged journals mounted in journal boxes, provided with slots in their upper surfaces 40 smaller than said enlarged journals and larger than the body of the rod, the ends of said coupling rod being bent and adapted to normally retain said rod in operative position within its bearings.

4. In a coupler release rigging, an uncoupling rod provided with a plurality of enlarged journals mounted in journal boxes, provided with slots in their upper surfaces 50 smaller than said enlarged journals and larger than the body of the rod, stops on said rod adjacent to the journal boxes adapted to normally retain it in operative position within its bearings.

In testimony whereof we hereto affix our signatures.

LOUIS G. MILLER.
FREDERICK C. DANKMYER.
